A. GROB, C. B. KECK AND F. J. BAIRD,
MEANS FOR ASSEMBLING COMMUTATORS,
APPLICATION FILED OCT. 31, 1919.

1,400,157.

Patented Dec. 13, 1921.

UNITED STATES PATENT OFFICE.

ARNOLD GROB, OF CLEVELAND, CHARLES B. KECK, OF WICKLiffe, AND FRED J. BAIRD, OF EAST CLEVELAND, OHIO, ASSIGNORS TO THE HOMER COMMUTATOR COMPANY, OF CLEVELAND, OHIO, A CORPORATION OF OHIO.

MEANS FOR ASSEMBLING COMMUTATORS.

1,400,157.

Specification of Letters Patent. Patented Dec. 13, 1921.

Application filed October 31, 1919. Serial No. 334,889.

To all whom it may concern:

Be it known that we, ARNOLD GROB, resident of Cleveland, county of Cuyahoga, and State of Ohio, CHARLES B. KECK, a resident of Wickliffe, county of Lake, State of Ohio, and FRED J. BAIRD, resident of East Cleveland, county of Cuyahoga, State of Ohio, have invented new and useful Improvements in Means for Assembling Commutators, of which the following is a specification, the principle of the invention being herein explained and the best mode in which we have contemplated applying that principle, so as to distinguish it from other inventions.

Our invention relates to means for assembling commutators, its object being to permit such assembly to be effected in an efficient and economical manner. The said invention consists of means hereinafter fully described and particularly set forth in the claims.

The annexed drawing and the following description set forth in detail certain means embodying our invention, the described means, however, constituting but one of various mechanical forms in which the principle of the invention may be applied.

In said annexed drawings:

Figure 1 represents a plan of a device embodying our invention.

Fig. 2 represents an axial section thereof.

Fig. 3 represents an axial section and end view of the interior or central tube which constitutes a part of the finished commutator.

Fig. 4 represents a plan of the inner assembly ring.

Fig. 5 represents a side elevation of such assembly ring.

Fig. 6 represents a horizontal section taken on the plane indicated by line "VI—VI" in Fig. 5.

Fig. 7 represents a plan of a modified form of the interior assembly ring.

Fig. 8 represents a fragmentary axial section of such modified form, and taken upon the plane indicated by line "VIII—VIII" in Fig. 6.

The illustrated embodiment of our invention comprises an annular ring 1, Fig. 4, which consists of a plurality of segments 2, the ring being shown as composed of three segments in this particular instance.

The outer lateral surface of this ring lies

in the surface of a cone, as shown, and the segments are separated from each other upon planes 4, which are inclined with relation to the axis of the ring. In the circumferential portion of each segment are formed registering grooves 5, in which lie respectively expandible or elastic bands 6. One of the segments is provided with two pins 7 respectively, which are placed in the grooves, the bands being placed so as to leave their free ends adjacent to these pins. The latter prevent circumferential displacement of the bands so that their free ends will not fall opposite one of the divisional planes. These bands, it will be noted, hold the segments of this ring together, but permit them to yield radially, and thus permit the ring as a whole to expand.

The interior diameter of this ring, which we shall refer to as the interior assembly ring, is such as will receive the commutator segments 8 when in their assembled position. The interior surface of the ring is cylindrical to conform with the outer cylindrical surface of the assembled commutator bars.

An outer annular assembly ring 9 is provided of unitary structure and having an interior conical surface 10 of the same inclination as that of the outer conical surface of the interior ring 1.

In using the above described device, we first take the interior assembly ring and assemble therein around the inner cylindrical surface, the required number of commutator segments 8, a strip 11 of mica insulation being placed between each complete segment, as shown in Fig. 1. The interior central tube 12, to which one of the annular end rings 13 has first been attached, by spinning the end of the ring thereon, is then inserted in the interior cylindrical space formed by the inner ends of the commutator segments, a V-shaped mica ring 14 having first been placed upon the upper conical surface of this ring 13, and a cylindrical paper insulation 15 having been placed between the inner surface of the segments and the tube 12, as shown in Fig. 2. A second V-shaped mica ring 14 is then placed upon the segments over which is slipped a second end ring or cap 13. The interior diameter of the ring 1 is such that when the segments, insulation and tube 12 are thus assembled, the assembly ring will be slightly expanded, as shown in

dotted lines in Fig. 5, in which condition the bands 6 will exert an inward radial pressure against the commutator bars or segments, and thus hold the entire structure together with sufficient force to permit the ring and the assembled contents thereof to be handled. Pressure is then exerted transversely so as to compress all of the segments and the insulation inwardly, and while under such pressure the other end of the tube 12 is spun as at 16, thereby holding the entire structure securely in place.

This transverse pressure is exerted by inserting the inner assembly ring in the interior of the outer ring 9, and then pressing the outer ring upon the inner ring so as to cause the conical surfaces which are in contact to effect the necessary pressure, as will be readily understood.

20 After the tube 12 has been riveted while the segments are thus under pressure, the interior ring is removed from the outer ring 9 and the assembled commutator removed from the ring 1.

25 The commutator may then be given its final finish, as will be well understood by those skilled in the art.

In Figs. 7 and 8, we have shown a modification of the interior assembly ring, which 30 consists, however, merely in locating the grooves 5 in the upper and lower surfaces of the ring, as shown. In other respects, the construction and use of the modified form is similar to that of the first described 35 form.

By inclining the planes of separation of the segments of the interior ring, as illustrated, it will be seen that the line of division crosses a plurality of surfaces of the 40 adjacent commutator segments or bars, and thus more securely and thoroughly holds them in place.

What we claim is:

1. In means for assembling commutators, 45 the combination of an outer holding ring; an inner multi-part ring adapted to receive and hold commutator segments in their assembled position and having an exterior surface conforming with the interior 50 face of said outer ring; and elastic means

for holding the parts of said multi-part ring together.

2. In means for assembling commutators, the combination of an outer solid or integral ring; a multi-part ring adapted to receive 55 and hold commutator segments in their assembled position, fitting within said outer ring and having its parts provided with registering grooves; and an expandable band in said grooves adapted to hold the parts 60 of said multi-part ring together.

3. In means for assembling commutators, the combination with an outer ring having an interior conical surface; of an expandible ring adapted to receive and hold commutator segments in their assembled position, and having its outer lateral surface lying in the surface of a cone, and adapted to fit within the conical interior of said outer ring.

4. In means for assembling commutators, a multipart ring composed of elements separated from each other on planes inclined to the ring's axis, and yieldingly held together.

5. In means for assembling commutators, a multipart ring composed of elements separated from each other on planes inclined to the ring's axis, and held together by means of one or more elastic bands.

6. In means for assembling commutators, a multipart ring having an outer lateral conical surface and composed of elements separated from each other on planes inclined to the ring's axis; said elements being yieldingly held together.

7. In means for assembling commutators, the combination with a multipart ring adapted to receive and hold commutator segments in their assembled position, and having its parts provided with registering grooves; of a resilient split contractile ring in said grooves adapted to hold said parts together; and means for holding said ring against circumferential rotative movement.

Signed by us, this 14th day of October, 1919.

ARNOLD GROB.
CHARLES B. KECK.
FRED J. BAIRD.
